[57] CLAIM

The design for a glass crack repair tool, as shown and
described.

DESCRIPTION

FIG. 1 is a top plan view of a glass crack repair tool,
showing my new design;

FIG. 2 is a front elevational view thereof, the rear view
being a mirror image;

FIG. 3 is a right side elevational view thereof;

FIG. 4 is a left side elevational view thereof; and,

FIG. 5 is a bottom plan view thereof.

FIG. 1

FIG. 2

FIG. 3

FIG. 4

FIG. 5
